(57) **CLAIM**

The ornamental design for the pocketformer, as shown and described.

DESCRIPTION

FIG. 1 is an upper rear perspective view of the pocketformer showing my new design.

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The pocketformer is used in reinforced concrete construction. The broken lines in the drawings are presented for illustrative purposes and form no part of the claimed design.
